UNITED STATES PATENT OFFICE.

BENJAMIN BRODIO, OF NEW YORK, N. Y., ASSIGNOR TO THE SUPERHEATER COMPANY, OF NEW YORK, N. Y., A CORPORATION OF DELAWARE.

BOILER WITH SUPERHEATER.

Application filed December 2, 1920. Serial No. 427,861.

To all whom it may concern:

Be it known that I, BENJAMIN BRODIO, a citizen of the United States, and resident of New York, N. Y., have invented certain new and useful Improvements in Boilers with Superheaters, of which the following is a description.

My invention relates primarily to structures in which the superheater is intimately associated with the boiler, the two being encased in the same housing, and heated by the same gases. The invention is however also applicable to cases where the two are not so closely associated.

The high degree of superheat demanded by modern practice can be obtained only by placing the superheater at a point where the gases coming into contact with it have not been cooled too much by intervening boiler surfaces. The steam flowing through the superheater on its way from the boiler to the engine abstracts heat from the superheater fast enough to prevent any undue increase in its temperature. When, however, there is no flow of steam through the superheater, as during periods when the engine is shut down, or when the boiler is being brought up to pressure, it may become necessary to protect the superheater against the danger of burning out, and my invention has for its object the provision of improved protective means for this purpose. I am aware that means to accomplish this end have been proposed before now, but the means herein described I believe to be entirely new.

For the purpose of illustrating my invention, I shall describe it as applied in two typical instances, shown in the accompanying drawings. In these drawings, Fig. 1 is a longitudinal central section of a locomotive boiler with my invention applied; Figs. 2 and 3 are enlarged detail views of portions of Fig. 1; Fig. 4 is a sectional view on line 4—4 of Fig. 3; Fig. 5 is a view like the left portion of Fig. 1 and illustrates a modification; Fig. 6 shows a longitudinal section of a water tube boiler equipped with my invention, Fig. 7 being a sectional view on line 7—7 of Fig. 6. Throughout the views portions have been omitted and broken away where this could be done without rendering the views obscure.

Products of combustion from fire-box 1 (Fig. 1) pass by way of the flues 2 and tubes

3 to the smoke-box 4 and thence out through stack 5. These products of combustion heat and evaporate the water within the boiler, much the greater part of the evaporation occurring above and at the sides and ends of the fire-box 1, and around the portions of the flues and fire-tubes immediately adjacent to the fire-box. The steam generated, in the boiler as ordinarily used, is permitted to pass freely from the point where it is liberated from the surface of the water to all parts of the steam space, including dome 6. From the latter, when the throttle is open, it flows through the dry-pipe 7 to the superheater header 8. The header 8 has two sets of chambers, designated by numerals 9 and 10 respectively (see Figs. 3 and 4), those of the first set all communicating with the cross-channel 11, and those of the other with cross-channel 12, there being no direct communication between the two sets. The superheater elements or units 13 are tubular structures, looping into the flues 2, and each of them has one of its two ends secured to a chamber 9 and the other to a neighboring chamber 10. The steam from the dry-pipe 7 is thus distributed to the superheater elements and delivered back by them in a superheated state to chambers 10 of the header. From these it flows by way of cross-channel 12, throttle 14, and steam pipes 15—16, to the steam chest 17.

So far as described there is nothing unusual in the arrangement. While the throttle is open, the steam flow through the superheater elements protect these sufficiently against any excessive heat. When the throttle is closed, the means for protecting them most commonly employed in the case of locomotives is a damper which interrupts the flow of the gases through flues. These means (not shown in the drawing) are superseded by my device, now to be described.

A dividing plate 18 separates the space above water-level $a-a$ into two parts 19 and 20 its location being such that by far the larger part of the steam generated is delivered into one of the parts—in the present case the part above the fire-box. The plate 18 extends, it will be noted, some distance below the water level $a-a$. The spaces 19 and 20 communicate with each other by means of pipe 21, equipped with the three-way valve 22. The third branch of the valve 22 connects with pipe 23, the

forward end of which opens into cross-channel 12 of header 8. The three-way valve 22 in the position indicated in Fig. 2 allows free communication between the parts 19 and 20 of the space above water level $a-a$, cutting off communication to pipe 23; while in its other position it allows free communication from 19 to cross-channel 12 through pipe 23, and interrupts communication from 19 to 20 through pipe 21. The safety valve 24 is secured to some point such as the steam dome 6, where it communicates with space 20.

The operation of my device is as follows:

- 15 When the engineer opens the throttle 14 he at the same time places three-way valve 22 into the position of Fig. 2. Steam rising from flues 2 and tubes 3 into space 20 will reach the steam dome 6 and the entrance to dry-pipe 7 directly; and steam delivered into part 19 will pass through pipe 21 into part 20 and so to dome 6 and dry-pipe 7.

When the engineer shuts the throttle 14, he also places three-way valve 22 into the position where flow through pipe 21 is interrupted and the entrance to pipe 23 opened. Steam is being liberated faster below part 19 and delivered faster into this part than it is into part 20. The direct flow from that part to which the greater part of the steam is delivered to that part to which less is delivered is prevented by plate 18, and a steam flow will occur from the former to the latter by the indirect way of pipe 23, the superheater, and dry-pipe 7, the flow occurring through the superheater and the dry-pipe in a direction opposite to that in which steam flows through them when the throttle is open. The rate at which steam is delivered from the water into the spaces 19 and 20 remaining unequal during the entire time that the throttle is closed, the flow will likewise continue during such period. Should the pressure of the boiler rise sufficiently to cause the safety valve 24 to open, the relief of pressure will occur from part 20 of the steam space, and the flow from part 19 through the superheater to part 20 will continue.

50 The steam flowing through the superheater on its way from part 19 of the steam space to part 20 absorbs heat from the superheater walls and so protects them against undue heating. It should be noted that the heat absorbed is not lost but is returned to the boiler by the steam.

For the flow to occur as indicated at times when the throttle is closed, it will of course be necessary that the pressure in part 19 be higher than in part 20. As a consequence the water level in part 19 will be somewhat lower at such times than in part 20. The difference in pressure however is very slight, as the flow is slow and the frictional resistance correspondingly small, so that the

depression of the water level spoken of is negligible. It is, moreover, offset by the comparatively violent ebullition in this region, which always tends to raise the water level at this point.

It will be evident that for the best results in the operation of the apparatus the part of the space above the water into which the steam is delivered from the superheater should be made relatively as large as feasible so it may offer the greatest storage space possible and cause the greatest possible amount of steam to flow through the superheater.

Instead of establishing communication between the two parts 19 and 20 of the space above the water level by means of a pipe such as 21, the same end may be accomplished by the means indicated in Fig. 5. The partition 18 is provided with an opening 25, which may be closed by the cover 26. This cover is moved, to open or close the opening 25, by means of the rod 27. 63 are guides for the cover 26. The figure shows an arrangement by which the motion of the cover 26 is automatically related to the opening and closing of the throttle. The rod 27 extends out through the stuffing box 28, and is linked in any preferred way to throttle lever 29, so that when the latter is moved to open the throttle, the cover 26 moves to open 25; and when the lever is pushed forward and the throttle closed opening 25 is likewise closed. The pipe 23 leads forward from part 19 of the space to the header, its communication with the space 19 being controlled by the valve 62. This valve is operated from rod 27 to which it is connected by arm 30 and link 31. When rod 27 is in the position shown, and opening 25 of partition 18 closed, valve 62 is open; and when rod 27 is in its other position, valve 62 is closed.

The operation of this varied form will be evident. With the throttle open, i. e., the handle of the throttle lever 29 pulled out or away from the boiler, valve 62 will be closed and cover 26 will be away from its seat on plate 18. Steam from 19 will therefore be free to reach space 20 and the inlet to the dry-pipe, and no steam will flow through 23. But with the lever 29 in its inner position, i. e. with the throttle closed, opening 25 will be closed and valve 62 open; so that a circulation of steam from 19 to 20 by way of pipe 23, the superheater, and dry-pipe 7 will occur.

It will be obvious that, if desired, the form of my device shown in Fig. 1 can equally well be made automatically operable by a single movement of the throttle lever; or that, on the other hand, the variation of Fig. 2 may be arranged so the valve 62 and the cover 26 are operated separately from the main throttle.

In Figs. 6 and 7 is shown an application of my invention to a water tube boiler.

The gases from the furnace 40, passing over the water tubes 41 and 42, heat and vaporize the water, the steam liberated passing to the rear headers 43 and 44, and by means of the pipes 45 to the steam drum 46. The water level in drum 46 is indicated at a—a. There is in a boiler of this type a strong downward circulation of water through the tubes 47 and 49 to the front headers 48 and 50. Plate 51, extending the entire length of the header, its lower edge being below the water level a—a, divides the space 52, into which pipes 45 discharge steam, from 53, to which no or practically no steam is delivered. The two spaces are connected by pipe 21^a, provided with the valve 22^a. This is a three-way valve, its third branch being in communication with the pipe 23^a. This pipe leads to the outlet header 54 of the superheater. The valve 22^a is a commercial type of three-way valve by means of which spaces 52 and 53 may be put into free communication, opening to pipe 23^a being closed; or the communications between 52 and 53 closed, and communication between 52 and pipe 23^a be established.

The superheater header 54 is connected by the superheater elements 55 with the inlet header 56. To header 56 the steam from space 53 is conveyed by means of pipe 57. Pipe 58, provided with a throttle 59, carries the superheated steam to the point of use.

A safety valve 24^a communicates with space 53.

The action of this form is quite similar to that first described and may be briefly stated as follows. While the throttle 59 is open, valve 22^a will be so set that it shuts off communication to pipe 23^a and establishes connection between the two parts 52 and 53 of the space above the water level. Steam delivered by pipes 45 into part 52—and this means substantially all the steam generated by the boiler—reaches part 53 and is conveyed by pipe 57 to the superheater, which it leaves by pipe 58 for the engine or other point of use.

If the throttle 59 is closed, three-way valve 22^a will be set to interrupt communication between 52 and 53 through pipe 21^a, and to establish communication between 52 and pipe 23^a. Steam delivered by pipes 45 into part 52 of the steam space will flow through pipe 21^a, valve 22^a, and pipe 23^a to header 54, thence through the superheater elements 55, thence to header 56 and so by pipe 57 to part 53 of the steam space. This flow is brought about by the pressure difference created by the fact that substantially all of the steam is delivered at one side of the partition 51. While flowing through the superheater as just stated the

steam will abstract sufficient heat to form an effective protection against excessive heating of the superheater.

While I have described the form of my invention which I prefer it will be evident that numerous variations are possible without a departure from the underlying principle. This will be true in applications of the idea to boilers of the kind with which I have illustrated, and even truer when it is applied to boilers of other types. Thus it will be obvious that the inventive idea disclosed herein will have to be varied in a number of respects when it is applied to a Stirling boiler, but its essential characteristics will remain the same. The appended claims are to be interpreted to cover such variations.

What I claim is:—

1. In apparatus of the class described, the combination of a boiler; means dividing the space above the water level into two parts to the first of which more of the steam is delivered upon its generation than to the second; means to put these two parts into direct communication; a superheater; a pipe connecting the second of said parts of the space with the inlet of the superheater; a valved pipe leading from the outlet of the superheater; and a pipe connecting the first part of the space with the outlet end of the superheater.

2. In apparatus of the class described, the combination of a boiler in which the space above the water level is divided into two parts to the first of which more steam is delivered than to the second; a superheater; means to convey the steam from the first part to the second when the main throttle is open, thence to the superheater, and thence to the point of consumption; and means to convey the steam, when the main throttle is closed, from the first compartment to the superheater and thence to the second compartment.

3. In apparatus of the class described, the combination of a boiler; means dividing the space above its water level into two parts of which the first receives more of the steam liberated from the water than the second; a superheater; means connecting the second part with the inlet of the superheater; a valved conduit leading from the outlet of the superheater; valved means connecting the two parts with each other; and a valved conduit leading from the first part to the outlet of the superheater.

4. In apparatus of the class described, the combination of a boiler having two separated steam and water spaces into the first of which more of the steam is delivered on its generation than into the second; a superheater; a conduit connecting the inlet of the superheater with the second steam and water space; a valved conduit leading from

the outlet of the superheater; valved means connecting the two spaces with each other; and a valved conduit leading from the first steam and water space to the outlet of the 5 superheater.

5. In apparatus of the class described the combination of a boiler in which the space above the water level is divided into two 10 decidedly unequal parts to the first and smaller of which more steam is delivered on its generation than to the second; a superheater; means to convey the steam from the first part to the second when the main throttle is open, thence to the superheater, 15 and thence to the point of consumption; and means to convey the steam, when the main throttle is closed, from the first part of the

steam space to the superheater and thence to the second part.

6. In apparatus of the class described, the 20 combination of a boiler; means dividing the space above its water level into two decidedly unequal parts of which the first and smaller receives more of the steam liberated from the water than the second; a super- 25 heater; means connecting the second part with the inlet of the superheater; a valved conduit leading from the outlet of the superheater; valved means connecting the two parts with each other; and a valved conduit 30 leading from the first part to the outlet of the superheater.

BENJAMIN BROIDO.
